(57) **CLAIM**

The ornamental design for an AC-DC power-over-ethernet power supply, as shown and described.

DESCRIPTION

FIG. 1 is a top front perspective view of an AC-DC power-over-ethernet power supply;

FIG. 2 is a top plan view thereof;

FIG. 3 is a bottom plan view thereof;

FIG. 4 is a left elevation view thereof;

FIG. 5 is a right elevation view thereof; and,

FIG. 6 is a front elevation view thereof, the rear elevation view being a mirror image.

The broken lines shown in the drawings illustrate portions of the AC-DC power-over-ethernet power supply that form no part of the claimed design.
